PROPORTIONAL DIVIDER TRIANGLE

Harmodio A. de Valle Arizpe, Colonia Portales,
Mexico, D. F., Mexico

Application December 19, 1936, Serial No. 116,828

2 Claims. (Cl. 33—104)

This invention relates to improvements in instruments of precision, and its objects are as follow:

5 First, to provide an instrument for use by students, draftsmen, and the like, which is so constructed and arranged as to enable the working out and delineation of certain mathematical and geometrical problems involving applied geometry, and this with speed and accuracy.

10 Second, to provide a simple and accurate device for the purpose stated above, in which all of the scales employed are uniform, resulting in a gain in accuracy over any such device in which the scales are non-uniform.

15 Other objects and advantages will appear from the following description, reference being made to the accompanying drawing, in which:

Figure 1 is a plan view of the improved triangle;

20 Figure 2 is a detailed cross section taken on the line 2—2 of Fig. 1;

Figure 3 is a detail cross section taken on the line 3—3 of Fig. 1;

25 Figure 4 is a diagrammatic view illustrating the use of the triangle in dividing a given line into a number of equal parts;

Figure 5 is a diagrammatic view illustrating the use of the triangle in inscribing a regular polygon in a given circle;

30 Figure 6 is a diagrammatic view of the triangle illustrating its use in mapping.

This invention will be best understood from a consideration of the following detailed description in view of the accompanying drawing, but it is to be understood that the invention is not confined to the disclosure, being susceptible of such changes and modifications which shall define no material departure from the salient features of the invention.

40 The so-called triangle 1 is intended to be made out of a sheet of Celluloid of a suitable thickness, or any other suitable substitute. In its general aspect the device is a 45° triangle, but inasmuch as the profile of the side 2 is cut on a curve the instrument is not a true triangle, but is substantially so, and for convenience in reference is herein called a triangle. The triangle includes the base portion 3 and the hypotenuse 4. Base and hypotenuse lines 5, 6 are inscribed in the 45 surface of the triangle at a slight distance in from and parallel to the respective base portion 3, and hypotenuse 4. These lines and all other inscriptions on the face of the triangle are preferably filled with a colored pigment so as to be 50 easily discernible.

A hole 7 is made through the triangle at the vertex of the angularly related lines 5, 6. This hole and all similar holes through the triangle, is tapered (Fig. 2) from the inscribed face toward the bottom of the triangle. This formation readily admits the sharp point of a pencil and at the same time confines the point to a very small area on the paper underneath. The operator has only to insert the point of the pencil when the mark on the paper will appear as little more than a dot. 10 This dot becomes a reference mark, as presently appears.

A similar tapered hole 8 is formed in the triangle 1 at the intersection of the base line 5 with a line 9 in continuation of the side 2 into the region of a horn 10 at the right terminal of the triangle. The hypotenuse line 6 stands at a 45° inclination to an index line 11, which is designated 90° line. This line is perpendicular to the base line 5, and it is used for the purpose of 20 establishing the perpendicularity of any given line with respect to the base line 5.

The face of the triangle is inscribed with a number of scales. These occur in two general divisions, one being marked off in a manner similar to the spacing of a ruler, the other consisting of spaced and numbered holes. It is contemplated that in practice holes other than those shown will be formed in the triangle at critically and accurately located places in order to enable 30 the solution of mathematical problems other than those herein explained. The scales in the first division are designated 12, 13 and 14. The scale 12 is regularly divided either in inches and fractions thereof, or, preferably, in centimeters 35 and millimeters. The scale 12 has left and right hand origins at the holes 1, 8, as shown by the sets of numbers 15, 16 which occur in increasing values toward the index line 11 where they stop.

40 The scale 12 is a scale of linear ratios or values and its markings end at one side of a slot 17 which extends in parallelism to the base line 5. This slot has slightly enlarged terminals 18, the left hand one of which occurs directly on a line 19 inscribed in the face of the triangle and marked 30° line, inasmuch as this line stands at a 30° inclination to the base line 5. The line 19 has its origin at the vertex 7 of the angle defined by the lines 5, 6 and 11. The purpose of the slot 45 17 is to enable the insertion of a pencil point so that a mark can be made on the paper opposite to the desired one of the divisions of the scale 12.

50 It is to be observed that the scale 13 is carried out only in part at the opposite extremities of the 55

base of the triangle. The obvious purpose here is to avoid running the scale markings up into the lines 6, 19 at the left and into the markings of the scale 14 at the right. Thus it will be understood that 12 and 13 are one and the same scale, the graduations at the left and right extremities simply branching off on opposite sides of the base line 5 to avoid confusion.

The scale 14 in the same division still under discussion is a uniform scale, graduated from 0 to 45° (a little over the 45° being shown). This scale is used in plotting on a map the results of certain surveying operations. Before proceeding with the scales in the second division attention is directed to the structure of the slot 17. In order to render the graduations 12 more definitely visible, one edge of the slot is beveled at 20 (Fig. 3). This bevel prevents the possibility of a shadow falling on the graduations 12 and thereby insures the visibility of the graduations. As a matter of convenience the graduations 12 and slot 17 are supplemented with the designation lines as at 21 so as to enable the user to distinguish from the second division of scales designated circles, as at 22.

This second division of scales consists of inscribed lines 23, 24, 25, upon which holes 26, 27, 28 are drilled through the triangle and tapered (Fig. 2). The series of holes along the respective lines 23, 24 and 25 are variously spaced and the holes are designated with numbers, as shown. A large hole 29 at a convenient place in the triangle aids the manipulation of the latter.

The use of the various scales is best understood from the description of a few examples, it being thought unnecessary to describe more than a few because in actual practice the triangle has many more uses than could be conveniently set out here. Reference is made to Fig. 4 which illustrates the problem of dividing a given line into an equal number of parts, say four equal parts. The given line 30 is located perpendicularly to the base line 5. This is done by resting the base portion 3 of the triangle 1 on a T-square and manipulating both until the given line 30 becomes parallel to the index line 11, whereupon the triangle 1 is slid to the right on the edge of the T-square out into view. Sliding continues until the extremities 31, 32 of the given line 30 coincide with the base and hypotenuse lines 5, 6.

The pencil point is now used to make a mark 33 on the paper through the hole 7 and a second mark 34 on the paper through that hole in the scale line 23 designated by the numeral 4. By now removing the triangle and using it to guide the pencil point for connecting the marks 33, 34 by a line 35, it will be found that the latter intersects the given line 30 at the point 36 which is one-fourth the length of the given line. The other numerals along the scale line 23 indicate other fractions into which given lines can be divided.

The next example selected is that of describing a regular polygon within the given circle 37, and reference is made to Fig. 5 for an outline of the operations. The polygon is intended to have nine sides, but the number may be more or less as will be understood from the numeral designations running along the holes in the scale line 24 which is the one now used. The center 38 of the circle is made to coincide with the base line 5, and the radial line 39 is placed perpendicularly to said base line according to the method described in connection with Fig. 4.

The triangle 1 is slid along the edge of the T-square until the circumferential point 40 touches the 30° line 19. A pencil mark 41 is now made on the paper through the hole 7 and a similar mark 42 is made on the paper through the hole 5 "9", this designating the number of sides of the polygon. A line 43 connecting the marks 41, 42 if extended far enough beyond the mark 42, will intersect the circle 37 at the point 44 which will be found to be one-ninth of the circumference. This measurement can be stepped off, as indicated at 45, and when corresponding measurements are connected by chord lines 46, the resulting figure will be a regular polygon.

A third and last example involves the use of the scale 14 in plotting on a map an observed inclination to the horizon of any given distance remote from a given stadia or observation station of the surveyor. The distance between two stakes or stations, measures along an inclined distance, is not given on the final map which will, therefore, show an apparent horizontal distance instead of the true condition of the terrain.

Suppose that the distance between two rods is 750 yards and that the observed vertical angle is 30°. According to Fig. 6, the triangle is placed on the map (not shown) in such a manner that the base line 5 coincides with the stadia station, and the course line 51 is perpendicular to said base line. This is accomplished by making the course line 51 coincide with the index line 11 and by sliding the triangle 1 along the edge of the T-aims until the course line is perpendicular to the base line and coincides at the point 47 where the scale 12 indicates a distance corresponding to the intercepted space on the stadia rod, in this case 750 yards as indicated at 48.

The horizontal distance is then completed by making a pencil mark 49 on the map through the hole 8, this being the origin of both the right hand side of scale 12 and of the scale 14. Another pencil mark 50 is made on the map at the place coinciding with the observed vertical angle, namely 30°. By connecting the marks 49, 50 with a line 53 which is extended far enough to intersect the course line 51, the point 52 where the intersection occurs denotes the proper reduced distance. Said point 52 will be the next transit station from which to lay off the succeeding course line.

I claim:

1. In an instrument of precision, a triangular body having a base line and a slot parallel to said base line, said body also having an index line perpendicular to the base line, a scale along said slot, the spacing of the slot from the base line being equal to one scale unit, said body having a hole at one end of the base line designating the origin of the scale, the relationship of said hole to the scale and base line enabling the notation of the scale divisions through said slot along said base line in the computation of mathematical formulas.

2. In an instrument of precision, a body having a pair of lines diverging from a point of common origin, one line of said pair of lines constituting a base line, a slot in said body parallel to said base line, and a scale between the base line and slot, beginning at said point of origin, said slot beginning at a point where a perpendicular to said base line at one of the graduations of said scale intersects the other line of said pair of lines.
